[57] **CLAIM**

The ornamental design for a cart for welding tanks, as shown and described.

DESCRIPTION

FIG. 1 is a side elevational view of a cart for welding tanks showing my new design, the broken line illustration of tank is for illustrative purposes only and forms no part of the claimed design;

FIG. 2 is a front elevational view of the cart with the tanks removed.

FIG. 3 is a rear elevational view of the cart similar to FIG. 2; and,

FIG. 4 is a top plan view of the cart, as shown in FIG. 1.
